UNITED STATES PATENT OFFICE.

DAVID A. RITCHIE, OF CENTRALIA, ILLINOIS.

LANTERN-SLIDE CARRIER.

1,173,740.

Specification of Letters Patent. Patented Feb. 29, 1916.

Application filed May 12, 1915. Serial No. 27,655.

To all whom it may concern:

Be it known that I, DAVID A. RITCHIE, a citizen of the United States, and a resident of Centralia, in the county of Marion and State of Illinois, have invented a new and useful Improvement in Lantern-Slide Carriers, of which the following is a specification.

My invention is an improvement in lantern slide carriers, and the invention has for its object to provide a carrier of the character specified, comprising a drum having illuminating mechanism within the same and mounted for rotation about the said mechanism and provided with peripheral apertures and holding means at the apertures for the slides, together with means for rotating the drum to bring any desired slide in position to be projected.

In the drawings:—Figure 1 is a perspective view of the improved carrier, Fig. 2 is a horizontal section, Figs. 3 and 4 are sections on the lines 3—3 and 4—4, respectively, of Fig. 2, and Fig. 5 is an enlarged detail section through the drum.

The present embodiment of the invention comprises a drum consisting of parallel laterally spaced disks 1, each of which has a central internally extending hub portion 2 to be later described. The hub portions are in alignment and are journaled on a shaft 3, which is supported in standards 4. The standards have feet 5, which may be secured to a floor or other supporting surface, and a ring is secured to each disk at the periphery thereof. Each ring is of angle material, comprising a portion 6 fitting the outer face of the disk, and a portion 6^a extending inwardly at right angles to the plane of the disk, the portion 6 of each ring being secured to the disk by means of rivets 7 or the like.

Strips or bars 8 are arranged transversely of the disks between the same, and at the periphery thereof, each bar being connected to the two rings of the disks and to the portions 6^a of the rings. As will be seen from an inspection of Figs. 3, 4 and 5 each of the strips or bars 8 is grooved in its opposite sides, and the said grooves are adapted to receive the side edges of the slides 9.

It will be noted that the strips or bars 8 are I-shaped in cross section and they are

spaced apart from each other just far enough to receive the slides between the adjacent strips or bars. The strips or bars provide guides for the slides, and the adjacent portions 6^a of the rings are spaced apart far enough to permit all of that portion of the slides which carry the picture to be at the opening. That is, the portion 6^a of the rings are spaced apart to form an annular slot or passage at the periphery of the drum, and this slot or passage has a width corresponding to the length of the pictured portion of the slide.

The hub portions 2 are spaced apart from each other at their inner ends to leave a space between the said ends, and illuminating apparatus is mounted on the shaft between the hub portions. This apparatus as shown more particularly in Figs. 2 and 4 comprises an angle bracket 10, having a hub or bearing 11, which encircles the shaft 3 between the adjacent ends of the hub portions.

A counterweight 12 is connected with one of the portions of the angle bracket, and illuminating mechanism is connected with the other portion of the bracket. The relative weight of the parts is such that the illuminating apparatus, which is arranged in a cylindrical container will be held with its axis horizontal and perpendicular to the shaft 3, while the weight 12 will depend below the shaft.

The apparatus comprises the casing 13, having its outer end open and flared as shown at 14, and having at its top a hooded outlet 15, for the heated gases. The illuminating mechanism proper is an incandescent bulb 16, supported in a suitable socket 17 below the hood 15, and a reflector 18 is arranged behind the socket. A suitable condenser 19 is arranged at the outer end of the casing between the flared portion and the body of the casing. It will be evident since the illuminating apparatus is counterbalanced on the shaft, that when the drum is rotated the said apparatus will hold the position of Figs. 1 and 2.

Projecting apparatus indicated generally at 19^a is arranged outside of the drum directly in line with the illuminating apparatus, so that the light rays thrown by the said apparatus will pass through the slide and

through the projecting apparatus. This projecting apparatus is supported by telescoping legs or standards, each of which comprises an outer tubular member 20, having a foot 21 for permitting the said member to be secured to the floor or like support and an inner member 22 slidable in the outer member.

The sections of each leg are held in adjusted position by means of a set screw 23 threaded through the outer member and engaging the inner member. The inner members are connected to the base of the projecting apparatus in any suitable or desired manner, and it will be evident that by loosening the set screws 23 the said supports may be raised or lowered and may be held in adjusted position.

The legs 4 before mentioned, are a part 20 of a frame, consisting of the said legs and other legs 4^a arranged on opposite sides of the projecting apparatus and in register with the adjacent legs 4. Each leg 4^a has a foot 5^a, for permitting it to be secured to 25 the floor and the upper ends of the adjacent legs 4 and 4^a are connected by horizontal tubular rods or bars 24.

The drum is rotated by a suitable motor 25, an electrical motor in the present instance, the shaft of which is provided with a pulley 26, and the motor is arranged adjacent to the drum at one end thereof. A table or plate 27 is secured to the bar 24 adjacent to the motor by means of clips 28 on the 35 under side of the plate or table, the said clips embracing the bar 24.

A bracket 29 is secured to the outer end of the plate or table, and a shaft 30 is journaled in the bracket parallel to the bar 24. 40 This shaft has a pulley 31 at its outer end, and the pulley is connected to the pulley 26 by means of a belt 32. A worm 33 is secured to the shaft between the bearings 34 in which the shaft is journaled, and the worm 45 is engaged by a worm wheel 35 on a shaft 36, journaled parallel with the shaft 3.

The worm wheel 35 is secured to the shaft 36 by means of a set screw 37, and the said shaft 36 is journaled in the bracket 29. A 50 mutilated gear wheel 38 is secured to the inner end of the shaft 36, and a disk or fly wheel 39 is secured to the outer end of the shaft. The gear wheel is provided with a series of teeth which are adapted to mesh 55 with a pinion 40 on a stub shaft 41, journaled in an upright or standard 42, extending upwardly from the table, and this stub shaft is provided with a radial arm 43, having at its outer end a laterally extending pin 44. The pin is adapted to engage the notches 45 in a wheel or disk 46, secured to the shaft 3.

It will be evident that when the shaft 30 is rotated by the motor, the shaft 36 will be driven thereby, driving the disk 38. Once

during each complete rotation of the disk the teeth thereof will engage and impart to the pinion 40 a complete rotation, there being the same number of teeth on the disk as there is on the pinion.

At each complete rotation of the shaft 41, the radial arm 43 will be revolved about the shaft, and for every complete revolution of the arm the disk or wheel 46 will be moved the distance between two adjacent notches, and the spacing of the notches corresponds to the spacing of the bars or strips 8. That is, every time the disk 46 is moved the distance between two notches one of the slides is moved away from in front of the illuminating apparatus, and another slide is brought into proper position before the same.

The disks 1 are provided with openings 47, which are normally covered by damper plates 48. These plates are pivoted to the disks at 49 to swing over and away from over the openings 47. Each of the plates has a finger piece 50 for convenience in manipulating the same, and it will be obvious 90 that the said plates may be arranged to uncover more or less of the openings as may be desired.

Each of the hub portions 2 is provided with a radial flange or rib 51, which fits 95 against the outer face of the disk, and is secured thereto by rivets 52 or the like. The disk or wheel 46 has a similar hub 53, which is secured to the disk in the same manner by rivets 54.

The operation of the carrier is as follows:—The slides are inserted in the guideways by moving them laterally and they are arranged directly over the annular passage between adjacent edges of the portions 6^a of the rings. When the slides are properly placed, the motor is started. The motor will drive the drum, bringing the slides in succession between the illuminating and the projecting apparatus, and it will be evident 110 that the pictures on the slides will be projected onto the screen.

By providing slides in series moving picture effects may be obtained. There is a positive stop between each movement of the drum, and with properly prepared slides moving pictures may be projected. The lamp support or illuminating apparatus retains its proper position regardless of the movement of the drum.

I claim:—

In a device of the character specified, a drum consisting of two spaced parallel disks, each having a hub, grooved strips connecting the peripheries of the disks and arranged at spaced intervals, said strips being grooved on the opposite faces to receive lantern slides between them, the strips and disks being spaced to leave an aperture of the proper size to permit the picture on the slide 130

to be projected on the screen, a hollow shaft on which the drum is journaled, a supporting frame for the shaft, an angle bracket mounted on the shaft between the hubs and 5 counterbalanced to hold one of the portions thereof horizontal and radial to the drum, illuminating apparatus on the said horizontal portion of the angle bracket, the hollow shaft being designed to permit the passage

of the controlling mechanism for the illuminating apparatus, said disks having damper controlled air inlets, and means for rotating the drum. 10
